HINGE

Homer G. Kellogg, Detroit, Mich., assignor to
Motor Products Corporation, Detroit, Mich., a
corporation of New York

Application September 26, 1928, Serial No. 308,480
Renewed May 12, 1931

12 Claims. (Cl. 16—163)

The present invention relates to hinges and more particularly to hinges especially adapted for use on the hoods of automotive vehicles.

Among the objects of the invention is a hinge structure that shall be capable of sealing the hood against the entry of dirt and moisture.

Another object is a hinge that is easy and economical to construct and assemble, and efficient in operation.

10 Other objects will readily occur to those skilled in the art upon reference to the following description and accompanying drawing, in which

Figure 1 is a perspective view of a hinge embodying the present invention, and showing one 15 end thereof.

Figure 2 is a sectional view of another form of the hinge.

Figure 3 is an enlarged sectional view showing the ideal form of the beads.

20 In the drawing the hinge structure is shown as of a form suitable for application to an automobile hood, that is, the protective covering usually placed over the motor. As is well known, such cover is usually hinged along its central longitudinal line and in such fashion as to permit the opening of either side in case it becomes necessary to do so.

In both figures of the present drawing, the hood proper is shown as formed of two sheet metal 30 leaves 10, each provided with a depending flange 11 by means of which it may be secured to the hinge structure, as by means of the rivets 12.

The hinge structure is shown in both figures as consisting of three parts, a body portion that 35 remains substantially stationary when the device is in use, and two angularly movable portions that are adapted to be secured to the hood proper as mentioned above.

In Figure 1 the body portion is shown as consisting of a strip of sheet metal bent longitudinally to form an arched central rib or bead and having its edges curved under to form one portion of a hinge such as is shown in prior application Serial No. 171,474, filed February 28, 1927, or in 45 Letters Patent, No. 1,666,211, issued April 17, 1928, both in the name of the present inventor.

In this figure, the body portion is indicated at 50 15 merging into the curved bead 17 which is formed into substantially a semi-cylindrical part 18, with the edge portion 19 turned up approximately vertical. The extreme edge portion 20 is provided with a further curved portion having a radius much shorter than that of the part 18.

55 The hinge portions on both sides of body 15 are

similar in form except that they are reversely curved and formed.

The other hinge part consists of a strip of metal in section substantially like an inverted L, the vertical stem 25 being the portion to which the hood member 10 is secured. The horizontal portion 26 of the strip has its edge formed into a downwardly extending bead 27 semi-circular in section on a radius of such length that it fits snugly within the semicircular portion 18 of the bead 17, while its extreme edge portion 28 is bent up close to the vertical but at a slightly greater angle thereto than is the portion 19 of the outer bead.

Further, this edge 28 is of such length that the curved portion 20 of the outer bead overlies or extends beyond as shown clearly in the drawing. This slight difference in the angularity of the edge portions 28 and 19 causes the former to press against the latter and obviate any relative movement of the two parts.

In the operation of the hinge, the member 15 remains stationary and the inner curved edge 27, which acts as the pintle portion rotates with in the part 17.

In the open position of the hood the hinge part carried by the hood members 10 engages the radially extending portions 19 of the other hinge part to limit the pivotal movement of the hinge parts in this direction.

In the form of hinge shown in Figure 2 the parts corresponding to those shown in Figure 1 are the hood members proper indicated at 10, the short strips to be riveted thereto are shown at 35 while the central member is indicated at 36. 90 In this form of hinge the central member 36 will be bent transversely to form the arched central portion and will have its edges curved in substantially the same sort of curve as at 18 in Figure 1, these curved portions being indicated at 37. 95

The curves, however, will be upward instead of downward as in the case of Figure 1. Also in this form the members 35 will be bent or curved inwardly as shown at 38 to give the same form to the hinge parts as has been described in connection with Figure 1.

In the operation of the hinge of Figure 2, the two curved edges will occupy the exactly reverse positions in opened and shut positions, to the corresponding positions of the parts of Figure 1. 105 That is, in Figure 1 when the hood is down, the hinge parts are turned into each other as far as possible while in Figure 2 they are turned out of each other.

In either case the hinge is closed throughout its 110

length to the passage therethrough of water or dirt and thus effectively protects the parts within the hood.

While it is preferred to form the L-shaped strips separate from the hood leaves proper, this is solely for convenience in manufacturing as the inner beads obviously may be formed integrally with the hood members if found desirable.

Figure 3 shows an ideal section, though this will of course be varied somewhat in the production of the hinge in quantity due to difficulties in handling thin metal. This figure shows clearly that all of the curves are concentric with the common axis lying in the central plane of the strip A and at such a distance from its inner edge that the distance to the edge corners equals the thickness of the metal. This latter distance is also the inside radius of the curve B. The radius of the inner curve of the part C equals the radius of curve B plus the thickness of the metal. The radius of the inner curve of part D equals the radius of part C plus the thickness of the metal. Such proportioning of the parts provides for maintaining the curved surfaces in contact during the hinging movement, so as to cause smooth operation and exert sufficient friction or pressure between the parts to prevent rattling even when they are most nearly disengaged.

Now having described the invention and the preferred forms of embodiment thereof, it is to be understood that the said invention is to be limited not to the specific details herein set forth, but only by the scope of the claims which follow:—

I claim:—

1. A hood hinge for motor vehicles comprising a central longitudinal member having its edges curved to form beads, hood members having at their adjacent edges cooperating beads curved to coact with the first mentioned beads, being embraced thereby, the curvature of the coacting parts being such that the adjacent curved surfaces are in contact during substantially the entire hinging movement, the extreme edges of the metal forming the beads being bent at different angles whereby to cause a pressure therebetween.

2. A hood hinge for motor vehicles comprising a central longitudinal member, arched transversely and having its longitudinal edges turned inwardly to form beads, and having the inner edges of the beads bent upwardly at an angle to the vertical, other hinge members adapted to be secured to the hood members and having coacting beads adapted to lie within the first mentioned beads and in contact therewith when said hinges are closed and to rotate therein in the opening of said hinges, the free edges of said latter beads being bent on an angle less than the first mentioned edges to press against the latter, for the purpose set forth, while maintaining contact.

3. A hood hinge for motor vehicles comprising a central longitudinal member arched transversely and having its longitudinal edges curved inwardly under said arched portion to provide longitudinal beads, and a pair of other hinge parts adapted to be carried by the hood members, extending up under said arched portion aforesaid and having their free longitudinal edges curved outwardly to form beads adapted to lie within the first mentioned beads, the free edges of each pair of coacting beads being bent at different angles to cause the corresponding beads to firmly engage one another.

4. A hood hinge for motor vehicles comprising a central longitudinal member having its longitudinal edges curved inwardly and upwardly thereunder and shaped to provide longitudinal beads constituting hinge parts, and a pair of other hinge parts carried by the hood members, said other hinge parts extending up under said longitudinal member and having their free longitudinal edges curved outwardly to form beads adapted to lie within the first mentioned beads for pivotal engagement therewith, one of each pair of beads having a radially extending edge portion engaging its cooperating bead to limit the pivotal movement of said hinge parts in one direction.

5. A hinge for independently pivotally connecting the adjacent edges of a pair of spaced hood sections of a motor vehicle comprising a stationary central longitudinal member of a width substantially equal to the distance between the spaced hood sections, beads constituting hinge parts formed on the longitudinal edges of said member, a pair of other hinge parts in the form of elongated strips, a bead formed on one longitudinal edge of each of said latter hinge parts having pivotal engagement respectively with the beads of said stationary member, the other longitudinal edges of said latter hinge parts being shaped to provide flanges for attachment to the spaced edges of said hood sections and being substantially in alignment with the longitudinal edges of said stationary member.

6. A hood hinge for independently pivotally connecting the adjacent edges of a pair of spaced hood sections comprising three elongated strips forming hinge parts, one of said hinge parts being stationary and substantially bridging the space between said hood sections, pivotal connections between the longitudinal edges of said stationary hinge part and one longitudinal edge of each of the two other hinge parts, the opposite longitudinal edges of said latter two hinge parts constituting flanges for attachment to the spaced edges of said hood sections and arranged in substantial alignment with the longitudinal edges of said stationary hinge part.

7. A hinge for connecting the independent hood sections of a motor vehicle hood the adjacent edges of which are spaced and include angularly arranged flanges, said hinge forming hinge supports for the separate hood sections and being composed of hinge members formed independently of the hood sections, said hinge including elongated strips formed with beads having interfitting pivotal engagement and provided with attaching flanges arranged in substantial alignment with the side edges of said hinge and attached to the flanges of the hood sections and the head of one hinge member having an inwardly extending part engaging its companion bead to prevent movement of the hinge parts in one direction.

8. A hinge for coupling independent and relatively movable body parts comprising three hinge members in the form of elongated and comparatively narrow strips, the central portion of one of said strips being slightly arched, and the side edges of said strip projecting downwardly and inwardly with respect to the concave face of the strip to form oppositely disposed and substantially cylindrical bearing members, the other hinge members being of substantially similar cross sectional form and having at one side thereof substantially cylindrical bearings adapted to be arranged and operated in the cylindrical

- bearings of the first named hinge member, and the other side of the second named hinge members forming attaching plates with which the independent body parts are coupled.
- 5 9. A hinge for pivotally coupling two independent body parts to permit independent and relative movement of said parts comprising a hinge arranged intermediate adjacent edges of said parts and forming a finishing strip disposed therebetween, said hinge comprising a stationary hinge member and two other hinge members adapted to be coupled with said body parts, and the second named hinge members having hinge connection with the first named hinge member to permit swinging movement of said body parts relatively to the stationary hinge member, and the stationary and second named hinge members consisting of elongated narrow strips of substantially the same transverse dimensions.
- 10 10. A hinge for pivotally coupling two adjacent independent body parts to permit independent and relative movement of said parts, said hinge being arranged intermediate adjacent edges of said parts and consisting of three elongated, narrow hinge members of substantially the same transverse dimensions, one member being stationary and forming a finishing strip disposed between said parts and the other hinge members being adapted to be coupled with said body parts, the second named hinge members having hinge connections with the first named member to permit swinging movement of said body parts relatively to the stationary hinge member, and the hinge connection between the first and second named hinge members being made by substantially cylindrical bearing portions arranged one within the other and coupled together by endwise, slidable engagement.
- 15 11. A hinge for pivotally coupling two adjacent independent body parts to permit independent and relative movement of said parts, said hinge being arranged intermediate adjacent edges of said parts and consisting of three elongated, narrow hinge members of substantially the same transverse dimensions, one member being stationary and forming a finishing strip disposed between said parts and the other hinge members being adapted to be coupled with said body parts, the second named hinge members having hinge connections with the first named member to permit swinging movement of said body parts relatively to the stationary hinge member, and the hinge connection between the first and second named hinge members being made by substantially cylindrical bearing portions arranged one within the other and coupled together by endwise, slidable engagement.
- 20 12. A hinge of the class described comprising three elongated, narrow hinge members of substantially the same transverse dimensions, one of said hinge members being adapted to be supported in stationary position and the other hinge members being directly and hingedly coupled with opposite side edges of the first named member, each of the second named members being adapted to be coupled with a support disposed at opposite side edges of the first named member and spaced apart thereby, and said first named member forming a finishing strip arranged between the adjacent sides of said supports.
